UNITED STATES PATENT OFFICE.

RUDOLPH B. HARTMAN, OF MILWAUKEE, WISCONSIN.

CONCRETE FLOOR CONSTRUCTION.

1,318,995.

Specification of Letters Patent. Patented Oct. 14, 1919.

Application filed April 10, 1913. Serial No. 760,113.

To all whom it may concern:

Be it known that I, RUDOLPH B. HARTMAN, of Milwaukee, Wisconsin, have invented Concrete Floor Construction, of which 5 the following is a specification.

This invention relates to concrete buildings and more particularly to the floors thereof; and the object which I have in view is to provide an improved system of floor- 10 construction which shall largely dispense with floor-forms and especially with the cutting, fitting and placing of wooden platforms which are made necessary by the system of construction at present in common 15 use.

Furthermore, I aim to provide a floor-construction system which shall economize in material, not only dispensing with the lumber necessary for the forms (except a small 20 portion thereof which can be repeatedly re-used), but also by using an inferior grade of materials and hollow spaces for a part of the floor where that can be done without reducing the strength.

25 A further object of the invention is to provide means for suspending beams and flooring directly from metal girders or I-beams where such are used in the general frame-work of the building.

30 Still a further object of the invention is to provide a simple and convenient device for regulating and adjusting the length of the wire used for drawing up the two sides of a wall-form, and for fixing the free end 35 of the wire.

My invention consists in the constructions and combinations hereinafter described and particularly pointed out in my claims.

In the accompanying drawings, which 40 illustrate the most improved forms of my invention,

Figure 1 is a plan view of the arrangement of a floor-construction showing the different elements thereof in position before 45 any concrete is poured;

Fig. 2 is a vertical section thereof taken on the plane 2;

Fig. 3 is a similar section on a larger scale of the I-beam or girder on the left of Fig. 1;

50 Fig. 4 is a perspective view of one of the supporting-and-fire proofing blocks shown in Fig. 3;

Fig. 5 is a transverse sectional view, on a larger scale than Fig. 1, of one of the joists 55 on the right of said figure and parts of tiles resting thereon;

Figs. 6, 7 and 8 are similar views showing alternative forms of the same;

Fig. 9 is a plan view of another arrangement of concrete-floor framework and forms 60 constructed according to my invention, showing different arrangements in each of the four panels into which it is divided, and a part of the filling slabs omitted;

Fig. 10 is a transverse section of the same 65 on the line 10—10, except that all of the filling slabs are inserted in this view;

Figs. 11 and 12 are side-views on a larger scale of a pair of cross-joists of the type 70 illustrated in Fig. 9;

Fig. 13 is a perspective view of one of the joists of Fig. 1;

Figs. 14 and 15 are side views of auxiliary devices which are used in filling the forms 75 of Fig. 1;

Figs. 16, 17 and 18 show alternative types of floor-construction which may be used instead of that shown in Fig. 1;

Figs. 19 and 20 are transverse sections 80 through other constructions of concrete floor and according to my invention;

Fig. 21 is a transverse section taken at right-angles to the view in Fig. 20, of Fig. 21, on the plane 21; Fig. 20 being conversely a section on the plane 20;

Fig. 22 is a perspective view of a part of the slab- and block-work of Fig. 19;

Figs. 23 and 24 are perspective views of elements for filling-slabs of the same type 90 as those shown in Fig. 20, except in forming closed panels instead of strips;

Fig. 25 is an end-view of Fig. 26, which shows my novel device hereinbefore alluded to for drawing up and adjusting the distance between the sides of wall-forms;

Fig. 27 is an end-view from the lower end of Fig. 26 of the device;

Fig. 28 is a perspective view of the wire-fastener shown in Fig. 26;

Fig. 29 illustrates a wire bend ready to 100 loop around the fastener;

Fig. 30 illustrates in perspective an alternative form of fastener; and

Fig. 31 is a side-view of a drill provided 105 with my pulling-in arrangement for wires.

The reference letters refer each to the same part in each figure of the drawings.

Referring first to the construction of Sheet 1 of the drawing, the elements may best be described by the manner and in the 110 order of erecting them. The floor is supposed to be divided into rectangular panels

which may be square or oblong, this construction being called the panel-system, as opposed to the so-called beam-system in which the main supporting beams run in one direction only. For the sake of showing that my invention is adapted for use either with the composite construction, with steel framework and concrete filling, or the all-concrete construction, I have shown in the upper left-hand corner and adjacent corners of the panel steel H-columns A, surrounded by a form-boxing a' adapted to hold a concrete covering, whereby the beams are fireproofed in the usual manner; and in the right lower corner of the panel I have shown an all-concrete column A' inclosed in a column-box a'' and having reinforcing rods a^2 . It is to be understood that the concrete itself which is poured in is not shown in the drawing, as it would obscure the other features, but only the space for it is shown.

Similarly on the upper and left-hand sides of the panel are shown metal girders or beams B, which are secured to the columns A in any usual manner; and on the lower and right sides of the panel, I have shown forms for concrete beams B', said forms comprising the usual bottom- and side-planks b' and b^2 , these planks serving further as supports for the rest of the framework on which the floor is supported and being themselves supported upon the column forms a' and a'' . The beam-forms b' and b^2 are further supported in the center by posts C having braced cross-arms.

In order to fireproof the lower portions of the beams B and likewise form a support for the floor corresponding to that given by the form-planks b^2 , said lower portion of each beam B is inclosed by a pair of rows of blocks D, each of which has a groove d' in one side adapted to receive the flange of the beam on the corresponding side, and each two opposing blocks D being σ shaped that when their faces d^2 come against the sides of the beam, the lower faces d^3 below the groove d' come together in abutting relation. This completely incloses the exposed portion of the I-beam and when the blocks are in place and the floor cast, they will be held in place by the concrete; but for temporarily or permanently holding them in place wires d^4 are cast in the blocks, projecting from the top and bottom sides so that they can be twisted together at d^4 and d^5 . Of course, when the floor is cast, the projecting ends of the wires can be cut off or plastered over.

Before going farther, it may be observed that the general principle of my construction herein disclosed is to arrange, as a substitute for the usual temporary wooden forms, a set of especially cast elements of

material which not only act as temporary forms for the concrete but also form a permanent part of the floor and of the supports thereof. These elements being made previously in the shop and brought to the place of erection, can be made and set more economically than concrete can be poured in place, and they have the added advantage that the reinforcement is all placed beforehand and these elements can be rapidly set in place without any cutting or fitting, being all shaped correctly according to the design and dimensions of the panel. Furthermore, the arrangement is such as more correctly to distribute the loads by placing a larger proportion nearer the columns and thus making the beam loadings correspondingly less. The construction has the further advantage of inclosing the bottom of the floor in a more or less insulating covering which prevents cold air from reaching the bottom of the freshly poured concrete before it is set; so that according to my system the delay due to freezing weather is very much less than on the wooden form system.

Having constructed the column and beam-forms as above described, I next divide the panel into four parts by cross-planks E and F, laid on a level with each other; their upper sides flush with the under surface of the floor. Plank E extends across the center of the panel and is supported at one end (at the lower side of the drawing) on the beam-form plank b^2 and at the other end it abuts against one of the blocks D on the inner side of the beam B and is supported by a post G and a braced cross-arm g' . There are two beams F similarly supported at their outer ends, and where they abut against the edges of the plank E in the center of the panel they are supported by a braced cross-arm h' on top of a post H, which further serves to support the center of the plank E. Intermediate posts I may also be used, as many as necessary to support the planks E and F at intermediate points. These planks E and F form the base-forms for quartering-beams dividing the panel into four subpanels, and are the only temporary pieces used in the floor-construction.

I next lay across the subpanels in parallel relation a number of cast-joists J, one end of each of which is supported by one of the form-planks E and F and the other end by a beam-form plank b^2 or block D as the case may be. I propose to cast these of the dimensions required in the shop before they are brought to the job, and preferably of concrete, inclosing the reinforcement rods j' , which extend beyond the ends of the beams as shown so as to form bonds with the concrete which is to be poured. The ends of these rods j' may, as shown on the right-hand end of the upper joist in

- the lower left-hand subpanel, extend across into the opposite subpanel if desired; and the ends where they cross the beam B may be hooked around the latter as shown in Fig. 3. 5. Each of the joists J carries on its lower margin, on each side thereof, a continuous rib or flange j^3 or one of the equivalent laterally projecting devices shown in the upper right-hand subpanel of Fig. 1 and in Figs. 6, 7 and 8; the purpose of these flanges or projections is to support a row of tiles K, whose edges are either grooved to lie upon said projections j^2 or otherwise so shaped according to the style of joists 10. 15. adopted that the bottom of the tiles is flush with the bottoms of the beams, as clearly illustrated in Figs. 5 to 8 inclusive, thus giving a perfectly flush surface to the under side of the floor. These tiles have the proper dimensions to fill the space between two adjacent joists J or between them and the sides of the subpanel, the outer rows resting upon the form-planks b^2 , blocks D or planks E and F, as the case may be. 20. 25. This completes and closes the panel and the concrete is now ready to be poured therein. The members K, herein termed tiles, may be of concrete or burnt clay, terra cotta, or similar material as desired. A convenient form is that known as "book-tile" shown on the left of Fig. 2, the edges of the tile being curved and interlocking. It will be understood, of course, that these tiles, as well as joists, need only be made strong enough to support the concrete while it is setting and they are not necessarily relied upon to form the support of the finished floor. Reinforcement-rods may be laid upon them directly and without the need of stirrups, since they will be substantially gripped by the concrete whether they contact with the tile or not; and the latter are also effectively cemented to the concrete. 30. 35. 40. Instead of the "ship-lap" joint shown in Figs. 1 and 5 between the tiles and joists, the alternative form of joists J' of Fig. 6 may be adopted, wherein the flange j^2 is omitted and its place taken by bars j^3 , preferably of band-iron, set transversely near the bottom of the joist and projecting laterally therefrom; and in place of the tiles K the form K' is adopted which has grooves formed in the side-edges adapting them to be slid endwise over the projecting ends j^3 . 45. 50. 55. Another form J'' is shown in Fig. 7, in which the place of the flange j^2 is taken by a beveled flange j^4 , and the edges of the tiles K'' are correspondingly beveled; while, as further supports, to prevent the tiles from falling down before the joists are set in place, transverse bars j^5 are inserted which project laterally from the bottom corners of the beam J'' as shown, being bent upwardly in the middle. The ends of the 60. 65. bars j^5 will, of course, project slightly from the under side of the ceiling, but they are not needed for support after the floor form is set up, because before casting the tiles and joists are pushed together so that the former are brought up tight into place. 70. 75. In Fig. 8 is shown a third alternative form J''' which is the same as the form of Fig. 7 except that the flange j^4 is omitted and a bar j^6 used with projecting ends similar to the bar j^3 . This is simpler than either of the other forms, and requires no special shape of tile, that used, K''', having plain edges. Of course, other forms may be devised consistently with my invention. 80. 85. In order to equalize the load on the central quartering-beams and also on the lateral beams of the panel, the joists of adjacent subpanels are arranged at right angles to each other. It will be seen that the effect of thus supporting the flooring by means of the quartering-beams and joists is to bring a larger proportion of the load carried by the side-beams nearer to the column-supports than would be the case in an ordinary plain slab-floor. 90. 95. Before pouring the concrete, all the pipes, wires, conduits and other surface appliances for the building may be laid in place between the joists and across the beams as may be desired, and this is done without any interference with the previous or subsequent work, which is a great advantage presented by my system of construction. Next comes the pouring of the main and quartering-beams, and in order to do 100 this without allowing the concrete thereof to spread into the subpanels, and also without erecting special form-work, I provide sets of temporary planks L and M, shown in Figs. 14 and 15, which are placed parallel and at right angles respectively to the joists on the sides of the subpanels. The temporary plank M, which is formed with notches m^1 at the proper intervals and of the proper dimensions to fit over the ends 110 of the joists J, is so placed that the bottom m^2 rests upon the tiles K, and the plank is leaned back slightly until the tops m^3 of the notches m^1 rest upon the top of the joists J; the plank L is then placed on the other open side of the subpanel and blocked up in a similar position. This being done on each of the open sides of the subpanels, the concrete is poured into the quartering-beams in the molds so formed at the same 115 time as the lateral beams B B', and it will be observed that these quartering beams will be wider at the top than at the bottom so as to increase the compressive strength and gain a good hold on the ends of the joists. 120. After sufficient time to permit the concrete to set sufficiently to hold its shape (usually a few hours will suffice for this), the planks L and M are removed and may be used elsewhere. The empty spaces between the joists 125 130.

may now be filled up with any cheap material such as ashes, cinders, cinder-concrete, etc., to give support to the floor-slab which is cast on top and whose upper surface 5 is represented by the line n in Fig. 1; this floor-slab may, of course, be as deep and go as far below the tops of the joists as desirable, depending on the depth of the filling material used. If cinder-concrete is 10 used for the filling, it will, of course, increase the strength of the floor. Where a wooden floor-surface is to be laid, furring-strips may be laid immediately on the joists J and secured thereto in appropriate manner 15 and the floor-boards laid on these, leaving the space between the joists J empty or containing only deafening-material. This finishing can all be proceeded with without waiting for the quartering-beams to harden.

20 As soon as they have assumed their final set, the planks E and F can be removed.

In place of using the combination of joists and tiles shown in Fig. 1, I may combine the joists and tiles into one of the three 25 forms shown in Figs. 16, 17 and 18. In Fig. 16, the floor-forms and supports are formed by T-shaped joists N , which may or may not be provided with wire-netting reinforcement n' and reinforcing-bars n^2 and 30 n^3 . In this case the joists sit together edge to edge. In Fig. 17 are shown a set of channel-shaped members N' which are also laid edge to edge and may or may not be provided with wire-netting or other reinforcement n^4 . In Fig. 18 are shown a set 35 of L-shaped members N'' which are also set edge to edge, and the heel of each L-shaped member is formed with a bevel-flange n^5 similar to the flange j^4 in Fig. 7, which engages 40 the correspondingly beveled end of the horizontal lap of the adjacent member N'' , and a further projecting bar n^6 , analogous to the member j^5 in Fig. 7, may be embedded in the concrete. In this case a 45 plain slab n^7 is used between the beam-form on one side of the panel and the heel of one of the members N'' , to avoid having the upright portion of the member come directly over the beam-form. These forms 50 of Figs. 16, 17 and 18, however, are not so usable in practical construction as the plane tile-and-joist construction, for the reason that they have to be made too heavy for handling without tackle, and it is one of 55 my objects that the floor-form shall be laid entirely by hand-work.

In Figs. 9 and 10 I have illustrated another manner of carrying out the principle of quartering, the same primary principle 60 which is shown in Fig. 1. The beams B' and their form-planks b' and b^2 , also the quartering-planks E and F , are substantially the same as in Fig. 1, unnecessary details being omitted. Instead, however, of using 65 parallel joists J , crossed joists O O' are used,

which, as in the upper left-hand corner of the panel, divide the sub-panel into four rectangular subdivisions; or if a smaller subdivision is desired, I may use the four joists O'' and O''' , crossing at right angles 70 and dividing the quarter-panel into nine rectangular subdivisions; or if a still smaller subdivision is desired, I may use the same method and an increased number of crossed joists, or preferably that shown in the right-hand lower subpanel, in which the two primary subjoists O and O' are supplemented with four sets of secondary crossed joists O^4 and O^5 . In this way each quarter-panel 75 may be divided as many times and into as many subdivisions as desired. Each of the crossed joists O , O' , O'' , O''' , O^4 , and O^5 , are provided with lateral flanges o' for the support of filling pieces, or formed with any of the corresponding equivalents shown in 80 Figs. 6, 7 and 8.

The method of forming these crossed joists is illustrated in Figs. 11 and 12, and also on the left-hand side of Fig. 10. The beam O is formed with a notch o^2 in the 90 center of its lower side of the same width as the joist O' , and the joist O' has a corresponding notch o^3 in the center of its upper side which has the width of the joist O ; and the combined depths of the notches o^2 and o^3 95 are equal to the depth of the joists O and O' ; the notch o^2 , however, is only of sufficient depth to permit the reinforcing bars o^4 of the joist O' to pass through it, said reinforcing bars being as near as possible to the bottom of the beam O' and the reinforcing-bars o^5 of the joist O being disposed immediately over said notch, but still low enough to serve their purpose. Thus each 100 joist has sufficient strength, it being observed, however, that the flexural strength of the joist O' depends upon compression against the sides of the joist O . The subsidiary crossed-joists O^4 and O^5 are, of course, 105 formed in the same manner, and thus the panel is divided into blocks small enough so that one of the filling-slabs P or P' is light enough to be handled by hand. The ends of the reinforcing-rods o^4 and o^5 will 110 normally extend beyond the ends of the joists, as shown in Fig. 1 and in Figs. 11 and 12, but for the sake of simplicity these are omitted from Fig. 9. In the case of the subjoists O^4 and O^5 , the ends thereof rest 115 upon the flanges o' of the primary joists, 120 and to prevent them from falling off in setting up the forms, the ends of the reinforcing wires o^6 are extended across the upper sides of the joists O and O' and twisted together as shown. The rectangular slabs 125 P or P' are now set in place, and the floor is finished as described for Fig. 1.

Where the floor is constructed according to the beam-system instead of the panel-system, my floor-construction will assume 130

one of the forms illustrated in Figs. 19 and 20, which show cross-sections parallel to the main beams of the completed floor with forms in position. In this case, first a series 5 of planks Q are laid at intervals corresponding to that of the concrete beams T which are to extend across at right angles to the girders to support the floor between. The planks Q are shown as supported on posts 10 q' which are braced and united by a transverse edgewise plank q^2 . Spanning these planks Q , there are now laid in position 15 rows of channel-shaped blocks R , each pair of adjacent planks being spanned by a row 20 of such blocks; and over said blocks, covering the hollow interior thereof, are placed slabs S , which may be notched as shown at S' on the right, or plain as shown on the left, of the figure. The outer faces of the 25 blocks R and slabs S have an overhung bevel to give them a firmer support from the concrete beams T , which are all ready to be poured as soon as the reinforcing-rods t' have been put in place. The blocks R and the slabs S or S' are preferably 30 disposed in staggered relation as shown in Fig. 22.

It will be observed that this style of floor involves a minimum of preliminary form- 35 work, and involves no building up except to place plain rough planks in position; and also involves great economy of material, since, in addition to the hollow spaces, the blocks R and slabs S S' can be made of 40 cinder-concrete, which has sufficient strength for the purpose and is much cheaper and lighter. The only full-strength concrete is in the beams T . Furthermore, the construction gives increased width at the top of the beam for compression.

A further development of this style is shown in Fig. 20, in which the planks Q , posts q' and planks q^2 , are the same except that the planks Q may be placed farther 45 apart. Instead of the blocks R , slabs R' are used; and instead of the slabs S or S' , arched members or bridge-pieces S'' , each of which may have a longitudinal strengthening-rib s^x . These are placed side by side in staggered relation as shown in Fig. 21, and the 50 beams T' immediately poured after placing the reinforcing rods t' . In this form, the slabs R' act as skewbacks or ties, temporarily at least, for the ends of the bridge-pieces 55 S'' , and are therefore formed with lugs r' which are engaged by lugs s'' on the latter, this engagement preventing any displacement of the bridge-pieces as well as the spreading of the ends thereof. Another 60 form of skewback-engagement is shown on the piece R'' at the left of Fig. 20, the bottom-member here being a plain slab provided with a notch r''' on each end which is engaged by a projecting angular rib s^3 65 on the end of the bridge-piece. Fig. 20 also

shows a third form of bridge-piece S'' , where the abutment is formed simply by driving nails r^3 into the face of the slab after it is set up. This is simpler of construction with less risk of breakage in trans- 70 portation, and it will be understood that the nails r^3 simply act as temporary alining devices for the bridge-pieces S'' . The tops of the bridge-pieces are made more or less angular according to the strength desired for 75 the beams T' and amount of concrete needed in the top thereof.

In Figs. 23 and 24 the same idea of the interlocking slab and bridge-piece is shown carried out in the form of a panel filler 80 adapted for one of the panel openings shown in Fig. 9. The lower member or slab U is made with a flange, rib or other abutment u' on all four sides to rest upon the flanges o' and the beams E and F , and the top or 85 bridge-piece V , which is shown upside down in Fig. 23, is likewise made with engaging lugs v' on all four sides and with transverse diagonal ribs v^2 connecting the corners. If made large enough this form can 90 be made to cover an entire quarter-panel.

In Figs. 25 to 30 inclusive, is shown my improved wall-form adjuster. The form-boards w' and w^2 are separated by the thickness of a concrete wall W , and, as well- 95 known, require stout tie-wires at intervals to prevent them from spreading. These tie-wires have to be tied up to prevent them from pulling out to an exact length and fastened, and it is a part of my invention to 100 enable it to be done readily and accurately as well as to store wire for the purpose. X indicates a spool or drum having an axle x' on which the wire is adapted to be wound and one or more holes x^2 there- 105 through for securing the end of the wire. On the axle x' are mounted two circular disks x^3 , whose function is to form a means of support for the axle x' upon the plank w^2 at a fixed distance therefrom. The ends 110 of the axle x' are extended beyond the disks x^3 at each end and given a polygonal, preferably hexagonal, shape x^4 , which acts in conjunction with a plate x^5 having a correspondingly shaped hole x^6 therein and 115 adapted to fit over one of the ends x^4 . The plate x^5 has a flat base x^7 adapted to rest upon the plank w^2 . The free end of the wire having been fastened in the manner hereinafter described or otherwise, the axle 120 x' is rotated and the wire so drawn up until the planks w' and w^2 are at the proper distance apart; then the aperture x^6 is engaged with one of the hexagonal ends x^4 in such a manner that the base x^7 rests upon the 125 plank w^2 . When the concrete is then poured, the strain of the wire tending to unroll it from the axle x' will be counteracted by the plate x^5 , whose flat base rests against the plank w^2 which prevents it from turning. 130

As a means for fastening the free end of the wire Y I prefer to use the simple contrivance illustrated in Fig. 28, which is simply a flat strip Z of wood or metal, preferably the latter, having a longitudinal saw-cut or slit z' of substantially the same diameter as the wire. To fasten the wire Y, a loop y' is formed by twisting the end y^2 once or twice around the body thereof, and 10 doubling the loop over so that the forked ends z^2 of the strip Z can be thrust through the loop, the twisted portion lying in the slit z' . The free end y^2 of the wire preferably lies flat on the under side of the strap 15 Z, so that it is compressed between the loop y' and the plank w' , and the twisted part being confined to the slit is prevented from untwisting and the number of bends formed by the wire assure it greater holding-power 20 than the force necessary to break the wire.

As an alternative form requiring a simpler fastening, I may use the strip Z' of Fig. 30, which has a tapered slit z^3 instead of the parallel slit z' , and a hole z^4 at the end opposite the slit. In order to fasten the wire with the aid of this strip, the free end y^2 thereof is inserted into the hole z^4 and preferably bent over with a hammer, then the wire is passed around one side of the strip and 30 into the slit z^3 so as to be jammed therein in the manner shown, and a notch z^5 may be placed in the edge of the strip Z' to assure greater stability as well as to guide unskilled workmen.

When the forms are to be removed, the wire Y can be immediately detached by cutting it opposite the slit z' or z^3 and the strip Z or Z' released.

While I have hereinabove shown the most improved forms of my invention, I wish it understood that not all of the features are essential thereto or necessarily made in the exact form shown, but various changes and modifications in the constructions as herein 45 shown may be made without departing from the spirit of my invention, and I wish it understood therefore that the latter is not otherwise limited than by the scope of my claims.

In order to draw the wires into place I find the arrangement convenient which is shown in Fig. 31. In the end of a twist-drill, or flat-end drill &, with which the holes are bored in the planks w' and w^2 , or 55 cleats or the like, for the wire Y, is formed a hole &. After drilling the holes through the wall-forms from side to side thereof, before extracting the drill, the end y^2 of the wire Y is inserted into the hole & and bent over as 60 indicated by the dotted lines. The drill being now extracted pulls the wire Y after it. If the wire is to be doubled it can be pulled through the hole a sufficient distance to form

a double length and then cut at the point of bending in order to remove the drill, and the 65 two ends twisted together over a strip such as the strip Z; or preferably, to avoid cutting the wire in this case, a notch &² is formed in one side of the drill, into which the wire can be looped and cast off without cutting. 70

Having thus described my invention, what I claim as new and desire to secure by Letters Patent is:

1. A substantially four-sided concrete floor-panel comprising inclosing-beams 75 along the sides, subbeams extending across the panel transversely to each other dividing it into four or more subpanels, said subbeams being monolithic with said main-beams, individually cast joists crossing each 80 other at right angles and extending across the subpanels dividing them into four or more individual spaces, said joists being notched where they cross each other whereby they fit flush with one another and having 85 lateral projections on the lower edges, individual slabs filling said individual spaces, the lower surfaces of said subbeams, joists and slabs being flush with one another, and a filling supported upon said beams, sub- 90 beams, joists and slabs to a floor-level over the tops thereof.

2. A substantially four-sided concrete floor-panel comprising inclosing-beams along the sides, subbeams extending across 95 the panel transversely to each other dividing it into four or more subpanels, said subbeams being monolithic with said main-beams, individually cast joists crossing each other at right angles and extending across 100 the subpanels dividing them into four or more individual spaces, said joists being notched where they cross each other whereby they fit flush with one another and having lateral projections on their lower edges, individual slabs filling said individual spaces; the lower surfaces of said subbeams, joists and slabs being flush with one another, and a filling support upon said beams, subbeams, 105 joists and slabs to a floor-level over the tops thereof; the joists notched from the upper side having a deep notch extending nearly to the bottom leaving a narrow neck and longitudinal reinforcing rods passing through said neck; and the joists notched from the bottom having a shallow notch and longitudinal reinforcing rods passing close to the top of said notch; and the width of the notch in any one beam being equal to that of the beam fitting in it. 115

In witness whereof I have hereunto set my hand in the presence of two witnesses.

RUDOLPH B. HARTMAN.

Witnesses:

FRED. A. BOUCHER, Jr.,
FELIX A. ABRAMS.
